UNITED STATES PATENT OFFICE.

GEORGE E. LEGENDRE, OF BRIDGEPORT, CONNECTICUT.

EXTRACTING-TOOL.

1,374,588.

Specification of Letters Patent.

Patented Apr. 12, 1921.

Application filed May 3, 1920. Serial No. 378,621.

To all whom it may concern:

Be it known that I, GEORGE E. LEGENDRE, a subject of the King of Great Britain, residing at Bridgeport, county of Fairfield, 5 State of Connecticut, have invented an Improvement in Extracting-Tools, of which the following is a specification.

This invention relates to extracting tools of the type adapted to withdraw cotter pins, 10 nails, spikes, or the like from their holding means, and the object of the invention is to provide a tool of this character which is extremely simple in structure, durable and efficient in use, and cheap to manufacture.

15 With the above and other objects in view, the invention comprises the construction, arrangement and combination of parts as now to be fully described and hereinafter specifically claimed.

20 In the accompanying drawing forming a part of this specification,

Figure 1 is a perspective view of the device of the invention, showing the manner in which my improved extracting tool is put 25 to use; and

Fig. 2 is a fragmentary, perspective view of a modified form of the invention.

10 denotes a ratchet bar and 11 denotes teeth thereon. The ratchet bar is removably 30 and slidably carried by a guide block 12 having ears 13 to which gripping levers 14 are pivoted as indicated at 15. Pivots socketed in the gripping levers, as indicated 35 at 16, are links 17 the opposite ends of which are pivoted to ears 18 on a slide block 19 arranged on the ratchet bar as shown. Spaced apart lugs 20 on the slide block 40 pivotally carry a pawl 21 which is adapted to engage the teeth on the ratchet bar, as disclosed in Fig. 1. A pin 22 passing through lugs 20 and the pawl is the means shown for supporting the pawl. It will be apparent that the pawl may be pivoted to the slide block in any ordinary manner. A 45 flat spring 23 attached to the lower portion of the pawl and resting against the slide block serves to normally hold the pawl in engagement with the teeth, as will be readily understood. As shown in Fig. 1, the lower

50 end of the ratchet bar is provided with a shank 24 having a hook 25 adapted to engage a cotter pin or the like. As shown in Fig. 2, the lower end of the ratchet bar carries a fixed jaw 26 and a pivoted jaw 27.

55 In Fig. 1 the manner of using the im-

proved extracting tool is suggested. 28 denotes a plate or the like through which is a bolt 29 carrying a castellated nut 30 and a cotter pin 31. To remove the cotter pin, the hook on shank 24 is inserted in the eye of 60 the pin, as shown, and the guide block is rested upon the top edge of the plate, or upon any suitable supporting means. When now the pawl is made to engage a tooth on the ratchet bar and the gripping levers are 65 pressed toward each other, it will be evident that the ratchet bar will be caused to slide upwardly through the guide block and the cotter pin will be withdrawn.

In the modified form of Fig. 2, the fixed 70 and pivoted jaws of the ratchet bar are first located about the nail, spike, or the like, to be withdrawn and the guide block is moved downwardly on the ratchet bar until its lower edge is about in line with the upper 75 portions of the jaws. When now the gripping levers are forced toward each other and the ratchet bar is thus caused to slide upwardly in the guide block, the jaws will pass into the lower portion of the guide 80 block and thus be held in gripping position on the nail, spike, or the like, being "pulled." It will be evident that in this form of the invention, as well as in the form disclosed in Fig. 1, the guide block must be 85 supported in fixed relation with respect to the nail or spike to be pulled before the gripping levers are operated.

The ratchet bar may be made any desired 90 length. Consequently, the supporting means for the guide block, in the case of the form of the invention disclosed in Fig. 1, may be located at any reasonable distance from the cotter pin, or the like, to be withdrawn. Likewise, the gripping levers may be made 95 any length and the links may be pivoted at any desired position on the gripping levers.

Having thus described my invention, I 100

1. An extracting tool of the character described, comprising a guide block and a slide block, a ratchet bar carried by said blocks, gripping levers pivotally secured to the guide block and having operative connection 105 with the slide block, and means carried by the slide block and adapted to engage the ratchet bar.

2. An extracting tool of the character described, comprising a guide block and a slide 110

- block, a ratchet bar carried by said blocks, gripping levers pivotally secured to the guide block and having operative connection with the slide block, and means carried by the slide block and adapted to engage the ratchet bar.
3. An extracting tool of the character described, comprising a guide block and a slide block, a ratchet bar carried by said blocks, 10 gripping levers pivotally secured to the guide block and having operative connection with the slide block, and a pawl pivotally carried by the slide block and adapted to engage the ratchet bar.
15. 4. An extracting tool of the character described, comprising a guide block and a slide block, a ratchet bar carried by said blocks, gripping levers pivotally secured to the guide block and having operative connection 20 with the slide block, and a pawl pivotally

carried by the slide block and adapted to engage the ratchet bar.

5. An extracting tool of the character described, comprising a guide block and a slide block, a ratchet bar carried by said blocks, 25 gripping levers pivotally secured to the guide block, links pivoted to the gripping levers and to the slide block, and a pawl pivotally carried by the slide block and adapted to engage the ratchet bar. 30

6. An extracting tool of the character described, comprising a guide block and a slide block, a ratchet bar carried by said blocks, gripping levers pivotally secured to the guide block, links pivoted to the gripping 35 levers and to the slide block, and a pawl pivotally carried by the slide block and adapted to engage the ratchet bar.

In testimony whereof I affix my signature.

GEORGE E. LEGENDRE.
